UNITED STATES PATENT OFFICE.

GEORGE W. RAWSON, OF CAMBRIDGEPORT, ASSIGNOR TO HIMSELF AND
MICHAEL HITTINGER, OF SOMERVILLE, MASSACHUSETTS.

IMPROVEMENT IN UPRIGHT STEAM-BOILERS.

Specification forming part of Letters Patent No. 140,729, dated July 8, 1873; application filed
December 18, 1872.

To all whom it may concern:

Be it known that I, GEORGE W. RAWSON, of Cambridgeport, of the county of Middlesex and State of Massachusetts, have invented a new and useful Improvement in Upright Steam Boilers or Generators; and do hereby declare the same to be fully described in the following specification and represented in the accompanying drawings, of which—

Figure 1 is a vertical section, and Fig. 2 a horizontal section of one of my improved boilers, the plane of section of the latter figure being taken just above the crown-sheet of the fire-place.

In such drawings, A denotes the fire-place, cylindrical in form and having a series of tubes, B, extended vertically from it and through its top or crown-sheet *a*, and a water and steam chamber, C, to and through the top of the latter and into a conical smoke-stack, D, erected over such chamber C in manner as shown. Within the said stack, and concentric therewith, and opening out of the chamber C, is a steam-superheating dome or vessel, E, provided with a discharge-pipe, F, arranged as shown. In the central part of the chamber C is a circulation-tube, G, supported by brace-rods H extended from it both to the top and to the bottom of the chamber. The said pipe does not extend down to the bottom of the chamber C, and the top of the pipe is to be below the level at which the water is to stand in the chamber while the boiler may be generating steam.

The object of this pipe is to cause, while the water in the boiler is being heated, a central downward current of water to be formed and to strike or impinge upon the crown-seat at its center and about such, in order to prevent the accumulation thereon of calcareous or other improper deposits which, without the pipe, will take place. Furthermore, the pipe and its brace or support rods greatly strengthen the boiler and counteract the strain on its up-

per head induced by the upward pressure of the steam in the dome. The stack of tubes B I arrange with diametric passages H', arranged through it and the boiler in manner as represented in Fig. 2, each of such passages, at its two opposite ends and just above the crown-sheet *a*, being provided with spy-holes *s s* formed through the sides of the boiler and provided with suitable caps, covers, or stoppers *t t*.

By removing the stoppers a person may see through the passages and over the center of the crown-sheet and remove any accumulations thereon by means of a scraper introduced into one of the holes, the opposite hole serving to light the passage. By having the steam-superheating dome or vessel E arranged within the smoke-stack it becomes subjected to the heat thereof, whereby the steam in the chamber, instead of being liable to be condensed, becomes superheated.

I make no claim to the combination of a steam receiver or dome with a boiler, such being in use on locomotive engines; nor do I claim a boiler with upright tubes or flues going through it and opening out of the fire-place; but

What I claim as my invention is as follows:

1. The circulation-tube G and the brace-rods H at its opposite ends, arranged within the water and steam chamber, or interior of the boiler, or with such and the superheating-dome E, and connected together and to the opposite ends of such boiler, all substantially as specified.

2. The tubular boiler having the diametric passages H' and spy-holes *s s* arranged between its tubes B and with respect to the crown-sheet of the fire-place, as set forth and represented.

GEO. W. RAWSON.
